UNITED STATES PATENT OFFICE.

JAMES F. IRWIN, OF PHILADELPHIA, PENNSYLVANIA.

SAFETY-ENVELOP.

SPECIFICATION forming part of Letters Patent No. 757,310, dated April 12, 1904.

Application filed December 16, 1903. Serial No. 185,432. (No model.)

To all whom it may concern:

Be it known that I, JAMES F. IRWIN, a subject of the King of Great Britain, residing at Philadelphia, in the county of Philadelphia and State of Pennsylvania, have invented new and useful Improvements in Safety-Envelops, of which the following is a specification.

My invention relates to new and useful improvements in safety-envelops; and its object is to provide an envelop of simple construction having means for accurately indicating whether or not the sealing-flap of the envelop has been opened subsequent to the sealing of the envelop.

With the above and other objects in view the invention consists of an envelop having a tab formed with one of the side flaps thereof and projecting through the bottom flap of the envelop, and said tab has an adhesive material thereon, whereby the same may be affixed upon the sealing-flap subsequent to the closing of the envelop.

The invention also consists of a tab which is so constructed as to be readily torn or marred, thereby accurately detecting the illegal opening of the envelop.

The invention also consists in the further novel construction and combination of parts hereinafter more fully described and claimed, and illustrated in the accompanying drawings, showing a preferred form of my invention, and in which—

Figure 1 is a rear elevation of a sealed envelop having my improved tab thereon. Fig. 2 is a similar view showing the envelop prior to the sealing operation, and Fig. 3 is an elevation of the adjoining ends of the side flaps of the envelop and showing the tab integral with one of the ends.

Referring to the figures by numerals of reference, 1 are the side flaps of an envelop, and formed integral with the free end of one of these flaps is a tongue 2, having a head 3, preferably provided with a series of minute perforations 4, whereby the same may be readily torn or otherwise injured. The tongue 2 is adapted to be inserted through an angular slot 5, formed adjacent the apex of the bottom

flap 6 of the envelop. This bottom flap is, subsequent to the insertion of the tongue 50 therein, affixed to the side flaps 1 in the usual manner. The envelop has a sealing-flap 7 of the usual form, and after this flap has been affixed in closed position upon the side flaps 1 the tongue 2 and head 3 are bent thereover 55 and affixed thereto, as shown in Fig. 1. It will therefore be understood that it is impossible to unseal the flap 7 without either first detaching the head and tongue from the sealing-flap or breaking the stem 2. The first-mentioned operation is rendered impossible in view of the fact that any attempt to detach the head will result in the tearing of the perforated head, and therefore it will be seen that the unlawful opening of the envelop will be promptly 60 indicated by the appearance of the tab. It will of course be understood that one face of the tab is suitably gummed, so as to permit it to be readily affixed to the sealing-flap.

In the foregoing description I have shown 70 the preferred form of my invention; but I do not limit myself thereto, as I am aware that modifications may be made therein without departing from the spirit or sacrificing any of the advantages thereof, and I therefore reserve the right to make such changes and alterations as fairly fall within the scope of my invention.

Having thus fully described my invention, what I claim as new, and desire to secure by 80 Letters Patent, is—

An envelop having side flaps and a slotted bottom flap arranged thereupon, a tongue extending from the inner end of one of the side flaps and through the slot in the bottom flap, 85 an enlarged apertured portion integral with the tongue and forming a head, and a sealing-flap adapted to overlap the side and bottom flaps and to be overlapped by and affixed to the apertured head.

In testimony whereof I affix my signature in presence of two witnesses.

JAMES F. IRWIN.
